UNITED STATES PATENT OFFICE.

PETER J. MACDONALD, OF BOSTON, MASSACHUSETTS.

REFRIGERATING APPARATUS.

SPECIFICATION forming part of Letters Patent No. 429,198, dated June 3, 1890.

Application filed May 18, 1889. Serial No. 311,277. (No model.)

To all whom it may concern:

Be it known that I, PETER J. MACDONALD, of Boston, county of Suffolk, State of Massachusetts, have invented certain new and useful Improvements in Refrigerating Apparatus, of which the following is a specification, reference being had to the drawing accompanying and forming a part hereof, in which I have shown an elevation of my apparatus partially in section for greater clearness.

My invention relates to that class of apparatus in which the refrigeration is obtained by the expansion of gas.

The object of my present invention is the construction of an improved apparatus by which a pure and dry gas may be obtained with a minimum wastage and pressure; and it consists in the peculiar construction and arrangement of the apparatus, as hereinafter described and claimed, as also in the employment therewith of a drip-chamber, whereby steam or moisture which may pass out of the gas-generating chamber with the gas will be condensed and separated from the gas and returned directly to the gas-generating chamber, as hereinafter set forth.

In my apparatus I use ammonia, and by the use of the improvements herein set forth I obtain the two effects which are most desired in an apparatus of this kind—viz., the production of the driest gas in the pipes and of the purest water in the gas-generating-chamber—that is, the ammonia in the driest form is most thoroughly and completely driven out of the watery solution in the gas-generating chamber.

My invention is simple and will be readily understood from the following description, in which reference is made to the accompanying drawing.

A represents a boiler, which may be of any desirable form, and which is arranged with a furnace underneath, the grate-bars of which are shown at B. One or more flues a pass from the fire box or chamber up through the boiler.

Inside the boiler A, I arrange a chamber D, having pipes b to accommodate the flues a, and somewhat larger than the flues, so that there will be a column of water surrounding the flues. The chamber D receives the am-

monia, which is placed therein in the form of aqua-ammonia, the strength of which may vary, but which contains usually about twenty-six per cent. of ammonia. The inlet to this chamber may be arranged in any suitable way. In the drawing it is shown at c, and the inlet to the boiler may also be in any well-known form.

A safety-valve is shown at d.

A pipe f passes from the gas-generating chamber D, being bent on itself, preferably, substantially in the form shown, and having connected with it the drip-chamber E. From the drip-chamber the pipe passes upwardly, and thence to the receiver H, into which it discharges.

Above the drip-chamber E the pipe f is surrounded by a sleeve g, having a funnel-shaped top to receive the water which may be poured or run into it, and having an outlet-pipe h to allow of the discharge of the water. This device is a dehydrator and is for the purpose of allowing a column of cold running water to be kept constantly around a portion of the pipe f. A similar device is provided on the pipe f just above the receiver H, as shown at j, which may be used, if desired, and by which a stream of cold water may be kept constantly flowing around that portion of the pipe f. A faucet is provided in the pipe f at k, near the ammonia-chamber, by which the pipe may be closed when it is desired to cut off the escape of the gas from the chamber. A similar faucet is provided for closing the pipe at I, near the receiver H.

From the receiver a pipe m passes to the refrigerating-chamber J, where it is bent in a series of coils n, and thence passes back in the manner shown to the cylinder p of a pump, which acts to force any ammonia which may pass through the pipe m back into the gas-generating chamber D. The steam-cylinder of the pump is shown at q, and the pump is operated in any well-known manner, preferably by steam from the boiler. By this arrangement the ammonia which passes from the receiver through the refrigerating-chamber is pumped back into the gas-generating chamber within the boiler.

The drip-chamber E is connected with the

pipe *f* by a connecting-pipe which is provided with a faucet *r*, a similar faucet being provided below the drip-chamber in the pipe *s*, which leads from the drip-chamber to the return-pipe *m*, as shown.

The drip-chamber is provided with a glass gage *t* to indicate the amount of liquid within it.

A pressure-gage *u* is provided on the receiver *H* to indicate the amount of pressure therein, and a gage *w*, similar to that on the drip-chamber, is also provided on the receiver to indicate the amount of liquid therein. The return-pipe *m* is also provided with a funnel-shaped inlet *y*, provided with a suitable stop-cock, by means of which that portion of the pipe *m* may also be filled with aqua-ammonia, so as to serve as an additional receptacle to the gas-generating chamber *D*. By making this portion of the pipe *m* long enough a very large quantity of aqua-ammonia may be stored, which will be pumped into the chamber *D* as the solution in the chamber is exhausted, so that the same result is obtained as if the chamber *D* were made very much larger.

The operation of the device is as follows: Water being placed in the boiler *A* and aqua-ammonia in the chamber *D*, the stop-cock *k* is opened and a slow fire is placed in the furnace beneath the boiler, and as the water in the boiler heats gas is generated in the chamber *D* and passes through the pipe *f* to the receiver *H*, the stop-cock at *x* in the pipe *m*, which leads from the compressor, being closed. In this way the receiver is charged with dry gas while the temperature of the boiler is still low. When the pressure in the receiver is sufficient, at which time the gas therein will be liquefied, the stop-cock *x* is partially opened and the gas is allowed to pass through the pipe *m* in the refrigerating-chamber. As the ammonia in the chamber *D* becomes exhausted and the heat increases, some moisture in the form of steam or vapor is liable to pass with the ammonia into the pipe *f*. To condense this vapor and prevent it passing over with the ammonia-gas, a stream of cold water is run through the jacket. (Shown at *g*.) This operates to condense the watery vapor, which after condensation, passes down into the drip-chamber *E*, the stop-cock at *r* being open. As this watery vapor passes into the drip-chamber *E*, it will probably take a small percentage of ammonia with it. When the drip-

chamber has been filled in this way, (the stop-cock below the chamber at *r'* in the pipe *s* being shut,) the stop-cock *r* is closed and the stop-cock *r'* is opened. The opening of the stop-cock *r'* allows the liquid in the drip-chamber to pass down through the pipe *s* into the return-pipe *m*, and thence to be pumped back again through the pump-cylinder *p* into the chamber *D* with the exhausted gas, which passes from the refrigerating-chamber in the return-pipe *m*. After the drip-chamber has been emptied in this way the stop-cock at *r'* is again closed and that at *r* opened, and the operation repeated.

I have shown the receiver *H* as surrounded by a receptacle *z*, which may contain cold water or brine. This receptacle I do not consider necessary, although I prefer to use it.

A check-valve of any well-known form may be inserted in the return-pipe *m* to prevent the gas in said pipe from going toward the refrigerating-chamber. Such a check-valve is indicated at *b'*.

It will be obvious that the extent of the pipe *f*, which is surrounded by the cold-water jackets *g* and *j*, may be varied as desired. By the use of the drip-chamber *E* all of the gas which passes into the receiver, whether under a high or a low heat, and whether the ammonia in the chamber *D* is nearly exhausted or not, is kept dry, while the wastage is reduced to the minimum.

Reference is herein made to my application, Serial No. 312,947, which shows and describes a refrigerating apparatus similar in general construction to that above described.

What I claim is—

A refrigerating apparatus consisting of a gas-generating chamber, an outlet-pipe therefrom, a receiver connected with said pipe, a refrigerating-chamber, and a pipe leading from said receiver to said refrigerating-chamber and thence back to the said gas-generating chamber therefor, in combination with a drip, a dehydrator and chamber connected with the outlet-pipe from the gas-generating chamber, said drip-chamber being provided with a discharge-pipe directly connected with the return-pipe from the refrigerating-chamber, for the purpose and substantially as shown and described.

PETER J. MACDONALD.
